(57) CLAIM

We claim, the ornamental design for a lipstick container, as shown and described.

DESCRIPTION

FIG. 1 shows a front, elevation view of a lipstick container, showing our new design;

FIG. 2 shows a side, elevation view thereof, the opposite side being a mirror image thereof;

FIG. 3 shows a bottom perspective view thereof;

FIG. 4 shows an exploded, top perspective view thereof;

FIG. 5 shows an exploded, bottom perspective view thereof;

FIG. 6 shows a top plan view thereof; and,

FIG. 7 shows a bottom plan view thereof.

The broken lines shown in the drawings illustrate a portion of the article and form no part of the claimed design.
